(57) **CLAIM**

I claim the ornamental design for a reversible head cover with attached endless scarf, as shown and described.

DESCRIPTION

FIG. 1 is a perspective view of a reversible head cover with attached endless scarf, showing the new design as it appears when worn;

FIG. 2 is a perspective view thereof, but showing the reversible head cover of FIG. 1 worn in a different manner;

FIG. 3 is a rear elevational view of the claimed design of FIGS. 1-2 when laid flat;

FIG. 4 is a front elevational view of the design as shown in FIG. 3;

FIG. 5 is a right-side elevational view of the design as shown in FIG. 3, the left-side elevational view being a mirror image thereof;

FIG. 6 is a top plan view of the design as shown in FIG. 3;

FIG. 7 is a bottom plan view of the design as shown in FIG. 3; and,

FIG. 8 is a right-side elevational view of the design as shown in FIG. 3 turned inside-out, the left-side elevational view being a mirror image thereof.

The broken lines showing a person in FIGS. 1 and 2 are included for the purpose of illustrating the invention in use, and form no part of the claimed design. It is understood that the views of the claimed design when it is turned inside-out would be the same as those shown in FIGS. 1-4 and FIGS. 6-7, with the exception of the contrasting inside surface (shown shaded in FIG. 8).
